UNITED STATES PATENT OFFICE.

JOHN GOOD, OF BROOKLYN, NEW YORK.

MEANS FOR CONTROLLING THE UNWINDING OF THREAD, TWINE, AND CORD FROM BOBBINS AND SPOOLS.

SPECIFICATION forming part of Letters Patent No. 352,312, dated November 9, 1886.

Application filed December 5, 1885. Serial No. 184,798. (No model.)

To all whom it may concern:

Be it known that I, JOHN GOOD, a citizen of the United States, residing in the city of Brooklyn, in the county of Kings and State of New York, have invented a new and useful Improvement in Means for Controlling the Unwinding of Thread, Twine, and Cord from Bobbins and Spools, of which the following is a specification, reference being had to the accompanying drawings.

This invention relates to what may be termed "gravity traversing guides," used in connection with upright bobbins and spools for controlling the unwinding of thread, twine, or other spun or twisted material therefrom, such guides being suspended from the thread, twine, or cord at a point near its delivery from the bobbin or spool, and having a traversing movement relatively to the spool to follow the coils of the thread, twine, or cord thereon from end to end thereof.

The object of this invention is to adapt such guides to a heavier class of machinery than that to which they have been heretofore commonly applied, and especially to adapt them to balling-machines for balling heavy twine and cord; and the invention consists in the novel construction of parts, hereinafter described and claimed, whereby the desired result is obtained.

The accompanying drawings represent my invention applied to the supply-bobbin of a machine.

Figure 1 represents an elevation, partly in section, of a bobbin and its support having my invention applied. Fig. 2 is a plan of the same. Fig. 3 is a vertical sectional view of the gravity traversing guide and its appurtenances, taken at right angles to Fig. 1.

Similar letters of reference indicate corresponding parts in the several figures.

A in the drawings designates part of the top framing of a balling-machine, which forms the base of the bobbin-support, the other parts 45 of said support consisting of fixed upright posts C C' C' and a cap, B.

D is the bobbin fitted loosely to an upright spindle, E, which passes through the cap B of the support and enters a loose bushing, f, which 50 is fitted into a bearing in the base A, and which is integrally formed with the friction-disk F.

The foot of the bobbin is attached to this friction-disk in the usual way of attaching bobbins to such disks, or in any suitable manner, so that the said disk is compelled to turn with 55 the bobbin, and the whole weight of the bobbin and the twine upon it and of the friction-disk is supported on the base A, between which and the said disk is placed a friction-pad, f', of canvas, leather, or other soft material, to equalize the friction which is produced between the bobbin and its supporting-base A by the weight above mentioned and the rotation of the bobbin.

G is a guide, consisting of a sheave pivoted 65 in a fixed position to the cap B of the bobbin-support.

H designates the principal parts of the gravity traversing guide, consisting of a hanger, H, and a broad sheave, h, pivoted thereto, the said hanger being fitted to slide freely on the upright posts C C' of the bobbin-support parallel with the axis of the bobbin, the said posts C C' being set far enough apart to receive between them the broad sheave h, the sheave-holder h', which will presently be described, and the part of the hanger H below them, and thereby keeping the planes of rotation of the said sheave in proper relation with the bobbin and the unwinding twine or cord. The 80 combined weight of the hanger H and its sheave may be properly proportioned relatively to the tension or drag on the yarn produced by the friction between the bobbin and its base; but as this proportion may require to be adjusted 85 or varied to suit varying circumstances, I attach to the hanger by screws or otherwise a weight, a, which may be changed for a heavier or lighter one, and I provide on the bottom of the hanger H an eye, b, into which may be 90 hooked an additional weight, as may be necessary.

In order to prevent any jerking on the twine by the loaded traversing guide hung thereon between the bobbin and the guide G, I do not 95 pivot the sheave h directly to the hanger H, which constitutes or carries the load of the traversing guide, but I pivot it into a forked holder, h', which is fitted to slide freely and vertically within the hanger, and the lower 100 part of which is connected with the hanger by a spring, h², so that the hanger and any weight

attached to it is suspended from the sheave and through it from the twine, through the medium of the spring, which, to a great degree, counteracts the effects of the jerking 5 which might otherwise be produced by the changes of direction of the guide and its load.

In the drawings the twine is represented as passing from the guide G to and under a stationary guide-sheave, I, and thence to a guide-sheave, J, in the head K of the flier of the balling-machine. These guide-sheaves constitute no part of the present invention, but are elements of combination forming part of certain improvements in balling-machines 15 which are the subject of my application No. 187,691, filed January 5, 1886, for United States Letters Patent, and they are only represented here to give such illustration as may be required in this specification of the practical application of this invention.

In the operation of my invention the twine *t* passes from the bobbin D to and under the sheave *h* of the traversing guide, thence upward over the sheave G to any take-up appa-

ratus or machine in connection with which the 25 invention is used. As the twine is unwound from the bobbin, the gravity-guide traverses the whole length of the bobbin, causing the draft of the twine to be at all times in planes parallel with the planes of rotation of the bobbin, and the movement of the said guide, owing to its construction and the combination of its sheaves and hanger with each other and the fixed guide-posts C' C, is free from jerks and twists and perfectly steady and uniform. 30

What I claim as my invention, and desire to secure by Letters Patent, is—

The gravity traversing guide consisting of the combination of the hanger H, the movable sheave-holder fitted to said hanger, the sheave *h*, fitted to said holder, and the spring *h'*, connecting the said holder and hanger, all substantially as and for the purpose herein set forth. 35

JOHN GOOD.
